UNITED STATES PATENT OFFICE

RUSSELL R. POTTER, OF NEW YORK, N. Y., ASSIGNOR, BY DIRECT AND MESNE ASSIGNMENTS, TO DURABLE BRUSH CO., INC., A CORPORATION OF NEW YORK

HANDLE ATTACHMENT

Application filed October 7, 1927. Serial No. 224,537.

This invention relates to a novel handle attachment adapted for use in securing a handle to various articles, such as a brush, mop, etc.

5 The object of the present invention is to provide a simple and effective method of attaching a handle to such devices in a manner which provides a very strong attachment which does not become loose with use of 10 broken with abuse.

The usual method of attaching the handle to such devices is to cut a thread on the end of the handle, which is usually of wood, and screwing the same into a threaded hole in the 15 device. While this is a simple means of attaching the handle, it is open to some objections. The cutting of the thread on the wood handle weakens the same at the point where the greatest strain comes in using the device. 20 Also the threads tend to become worn, from frequent removals of the handle, and also to become loose from shrinkage. This results not only in the handle becoming loose but when subjected to abuse or when hit against 25 the floor, etc., but the handle frequently breaks off at the point where it is screwed into the brush.

I overcome this and other objections by avoiding any threaded connection between 30 the handle and brush and by providing a metal strip, which is permanently secured to the handle, and which is shaped to extend partially around or across the back portion of the brush. Furthermore, the back portion 35 of the brush is grooved to receive this metal strip, which fits snugly in this groove, and which is secured in place by a stud or bolt passing through the brush and provided with a wing-nut, or other suitable fastening, by 40 means of which the strip is securely held in place in the groove. The end of the handle is also preferably reinforced by a ferrule and the three parts, the handle end, the ferrule and the strip, are firmly secured together by 45 rivets or bolts passing therethrough, as will be shown more in detail hereinafter in connection with the description of the embodiments of the invention illustrated in the accompanying drawings.

50 In the drawings, Fig. 1 is a plan view of the

device showing the handle attachment as applied to one form of a brush; Fig. 2 is a cross-sectional view, taken on the line 2—2 of Fig. 1; Fig. 3 is a view similar to Fig. 1, showing a modification of the attachment; Fig. 4 is a cross sectional view, taken on the line 4—4 of Fig. 3.

Referring to Figs. 1 and 2, a brush back of conventional form is shown at 1. At bolt 2 is passed through the back 1, with its threaded end extending outwardly and provided with a wing-nut 3. The handle 4 is slotted at its end and a metal strip 5 secured in this slotted end. This strip 5 is formed to conform to the shape of the back of the brush and is seated in a groove 6 which extends around the upper part thereof. This groove 6 is of such width and depth to permit a snug fit for the strip 5 when seated therein. It will thus be seen that this extended portion of the metal strip 5 seated in the groove 6 is snugly engaged throughout its length by the side walls of the groove and is prevented from turning relatively to the brush-back independently of the fastening bolt 2, which thus serves only to hold the parts together while the torsional stress is taken care of by the side walls of the groove, providing a rigid connection between the parts.

The end of the handle 4, which is slotted to receive one end of the strip 5, is provided with a ferrule 7, which encloses both the handle end and the end of the strip 5. Bolts or rivets, indicated at 8 and 9, secure the three parts tightly together, as described and shown.

The end of the strip 5 which is positioned in the groove 6 is provided with an opening slightly larger than the bolt 2, enabling the same to be placed over the bolt and secured in position in the groove 6 by the wing-nut 3. The handle preferably extends at an angle from the brush, as shown, and may be easily reversed in position by removing the wing-nut 3, which permits the handle to be removed from the brush and reversed in position thereon, as will be seen from a reference to the drawings.

In the modification shown in Figs. 3 and 4, the construction is similar to that just described in connection with Figs. 1 and 2,

except that the metal strip 5' is provided with an elongated opening 10 through which the bolt 2' passes, this bolt 2' being preferably set at an angle, as shown.

This not only provides for the removable and reversible feature of the construction shown in Figs. 1 and 2 but also provides for adjustment of the angular position of the handle on the brush, as indicated in dotted lines in Fig. 4. This is desirable in many cases with various kinds of brushes and other devices with which this attachment is adapted to be used for various purposes, as will be apparent.

15 While I have shown and particularly described this attachment for use with brushes, I do not wish to be understood as limiting myself to this use of the same, as it will be obvious that the invention is adapted to be utilized in connection with various handle attachments on many devices for various uses and that such changes and modifications as may be necessary to adapt it to such uses, without departing from the scope of the appended claim, are intended to be comprehended within the spirit and scope of the invention.

What I claim as new and desire to secure by Letters Patent is:—

20 In a device of the class described, in combination with an article to be provided with a handle, of a handle attachment comprising a handle provided with a metal strip secured to one end thereof and having an extending portion adapted to be secured to the article, said article being provided with a groove in which said metal strip is snugly positioned, the extending portion of said metal strip positioned in said groove being snugly engaged throughout its length by the side walls of said groove to prevent relative turning of said parts, fastening means on said article adapted to secure said strip securely in position in said groove and also permitting the same to be removed therefrom and to be reversed in position.

Signed at New York city, in the county and State of New York, this 27th day of September, A. D. 1927.

RUSSELL R. POTTER.
